UNITED STATES PATENT OFFICE.

WILLIAM G. WILSON, OF WEST NEW BRIGHTON, AND NESTOR L. JONES, OF MARINERS HARBOR, NEW YORK.

ANTI-RAIL-SPREADER.

1,216,903.

Specification of Letters Patent. Patented Feb. 20, 1917.

Application filed August 25, 1916. Serial No. 116,929.

To all whom it may concern:

Be it known that we, WILLIAM G. WILSON and NESTOR L. JONES, citizens of the United States, residing at West New Brighton and 5 Mariners Harbor, Staten Island, respectively, in the county of Richmond and State of New York, have invented new and useful Improvements in Anti-Rail-Spreaders, of which the following is a specification.

10 This invention relates to anti-rail spreaders, and has for its principal object the provision of a device of this character which will be adapted for use upon railway track structures, for the purpose of positively 15 holding the rails against relative separation whereby to minimize the possibility of the rolling stock leaving the track.

Another object of the invention resides in the provision of an anti-rail spreader which 20 may be expeditiously applied to or removed from the rails; one which will consist of mating sections adapted to be bolted together, and means for preventing longitudinal relative movements of the said sections so as to prevent the shearing of the 25 bolts incident to the side strains which are applied to the rails by the rolling stock passing thereover.

In the drawings:—

30 Figure 1, is a vertical section through the two rails of a track structure, showing the application of the invention thereto.

Fig. 2, is a plan view thereof.

Fig. 3, is a section taken on the line 3—3 35 of Fig. 1.

Fig. 4, is a perspective view of one of the mating sections of the device.

The device consists of two mating sections 1 and 2, each stamped from a single piece 40 of metal of the same uniform thickness throughout.

The member 1, is provided with a pair of clamping or securing lugs 3—3 which extend vertically from the upper edge of said 45 section and as shown these lugs are provided with angular faces 4, adapted to conform with the angle of the upper surfaces of the base flanges of the rails. The section 2, is provided with similar lugs 5—5 which 50 are adapted to be associated with the lugs 3—3 so that coinjointly all of the lugs co-operate as a common clamp to engage rails in a manner hereinafter described. The lugs 5—5 extend in an opposite direction to the 55 lugs 3—3.

The section 1, is provided with right angularly disposed end flanges 6—6 which are adapted to extend across the vertical ends of the section 2, when the latter is operatively applied to the rails. Both of said 60 sections 1 and 2 are provided with openings 7, through which clamping bolts 8, are adapted to pass. The bolts are employed for the purpose of holding the sections against relative lateral separation. Inci- 65 dent to the many side strains which are applied to the rails under the weight of the rolling stock, the bolts 8, are subjected to slight shearing action of the plate sections 1 and 2. We materially reduce the shearing 70 action of the sections 1 and 2, by forming the lugs or extensions 6—6 upon the plate 1. When the bolts are clamped tightly, the section 2, is moved against the section 1, causing the vertical ends of the former 75 to come directly behind the lugs 6—6 as will be understood.

Any suitable number of the devices may be arranged upon the rails according to the particular necessity, and in practice it will 80 be found that with the exercise of reasonable discretion an application of comparatively few of the devices upon the track will positively hold the rails against creeping or relative separation or spreading.

If desired strips of insulating material 85 may be interposed between the sections 1 and 2, and between the lugs 3—3 and 5—5, and otherwise suitably associated with the lugs or with the plates to form a proper insulation, when the device is used upon electrically charged rails.

In applying the device the section 1, is first slipped under the rails by moving and slightly canting the same. The lugs 3, are 95 then extended over the base flanges of the rails at one side thereof. The next section 2, is then applied so that the lugs 5—5 come over upon the base flanges at the opposite sides thereof. At such time the openings 100 7, in both of the mentioned sections 1 and 2, will be alined so that the bolts can be passed therethrough, for the purpose hereinbefore referred to.

What is claimed as new is:—

An anti-rail spreader comprising two mating plates of an equal thickness throughout and each of said plates at its upper edge and adjacent its ends being formed with lugs, the lugs upon the respective plates 110

adapted to coöperate with the lugs adjacent thereto to engage with the rail, the outer rail engaging lug of each of the plates being received in the fishing space of the rail which it engages whereby the upper edge of the said lug will underlie the head of the referred to rail, one of the said plates having angular ends whereby to receive the straight ends of the other plate, and means comprising clamping bolts passing through

both of the plates and serving to confine the hook-shaped lugs in operative position upon the rails and also to hold the angular ends of one of the plates against separating from the vertically straight ends of the other plate.

In testimony whereof we affix our signatures.

WILLIAM G. WILSON.
NESTOR L. JONES.
